J. PRIER

FOLDING CLOTHES DRIER

Filed Jan. 15, 1923

Fig. 3. Inventor
Joseph Prier
Watson E. Coleman
Attorney

UNITED STATES PATENT OFFICE.

JOSEPH PRIER, OF OBLONG, ILLINOIS.

FOLDING CLOTHES DRIER.

Application filed January 15, 1923. Serial No. 612,710.

To all whom it may concern:

Be it known that I, JOSEPH PRIER, a citizen of the United States, residing at Oblong, in the county of Crawford and State of Illinois, have invented certain new and useful Improvements in Folding Clothes Driers, of which the following is a specification, reference being had to the accompanying drawings.

- 10 This invention relates to certain improvements in folding clothes driers and it is an object of the invention to provide a novel and improved device of this general character having supporting arms adapted to be extended or retracted, said device with the arms retracted occupying a minimum of space and being capable for use as an article of furniture such as a clothes rack or the like.
- 15 The invention consists in the details of construction and in the combination and arrangement of the several parts of my improved folding clothes drier whereby certain important advantages are attained and the 20 device rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:—

30 Figure 1 is an elevational view of a drier constructed in accordance with an embodiment of my invention, a second position of certain of the arms being indicated by broken lines;

35 Figure 2 is an enlarged view in top plan of the structure as illustrated in Figure 1 with certain of the arms also indicated by broken lines in second position; and

40 Figure 3 is a fragmentary vertical sectional view taken through the upper portion of the device as herein disclosed, one of the arms being indicated in a second position.

45 As disclosed in the accompanying drawings, A denotes a vertically disposed skeleton structure comprising the upwardly and inwardly inclined corner posts 1 connected at their lower ends by the supporting sills 2. Mounted upon the sills 2 and substantially filling the space defined by the corner

posts 1 is a bottom board 3. At a point below but in relatively close proximity to the top end thereof, the corner posts 1 are connected by the cross members 5 provided on their upper surfaces with the angularly related notches 6 extending entirely thereacross. Each of the end notches 6 register with an open slot 7 provided in the upper portion of the adjacent corner posts 1. Interposed between and supported by the corner posts 1 and positioned above the cross members 5 is a board or plate 8. The lower face or surface of said plate or board 8 being substantially co-planar with the upper surfaces of the cross members 5. The 50 marginal portions of the board or plate 8 are provided with notches or recesses 9 which register with the notches or recesses 6 hereinbefore referred to.

55 As the cross members 5 are arranged outwardly of the corner posts 1 and the board or plate 8 positioned inwardly thereof said cross members 5 and the board or plate 8 are in stepped relation.

60 At a predetermined point intermediate the ends thereof the corner posts 1 are also connected by the cross members 5' constructed and arranged similar to the cross members 5 hereinbefore referred to and associated with said cross members 5' is the board or plate 8' constructed and supported in substantially the same manner as the board or plate 8.

65 Associated with each pair of registering notches or recesses 6 and 9 or 6' and 9' is an elongated arm 10. This arm 10 has disposed therethrough and extending beyond the opposite sides thereof the check pins 11, each of said pins being positioned a predetermined distance inwardly of an end 70 of said arm 10.

75 Each pair of registering notches or recesses 6 and 9 or 6' and 9' provides an opening through which the arm is freely slidable. When the arm 10 is in its retracted position it is disposed in a substantially vertical position with its outer end portion engaged within a notch or recess 9 or 9' and with the outer check pin 11 resting upon the upper surface of the board or plate 8 or 8'. When the arm 10 is extended it is substantially horizontally disposed with its inner portion seating within a notch or recess 6 or 6' with its inner end portion underlying and contacting with the 80

board or plate 8 or 8' and the inner check pin engaged with the inner face of a cross member 5 or 5'.

When the arms 10 are in their retracted position the device occupies a minimum of space and can be conveniently employed as an article of furniture such as a clothes rack or the like and for which reason the corner posts 1 are provided with the outstanding 10 supporting hooks 12.

By having the notches or recesses 6 and 6' angularly related a comparatively large number of arms 10 can be employed and in a manner whereby said arms when extended may have readily applied thereon clothes or the like to be dried without interference being given to one of the arms 10 by the arms adjacent thereto.

From the foregoing description it is 20 thought to be obvious that a folding clothes drier constructed in accordance with my invention is particularly well adapted for use by reason of the convenience and facility with which it may be assembled and operated, and it will also be obvious that my 25 invention is susceptible of some change and modification without departing from the principles and spirit thereof and for this reason I do not wish to be understood as 30 limiting myself to the precise arrangement and formation of the several parts herein shown in carrying out my invention in practice except as hereinafter claimed.

I claim:

35 1. A drier of the class described comprising upwardly and inwardly inclined corner posts, sills connecting the lower ends of the posts, cross members connecting said posts at a point below but in relatively 40 close proximity to the top ends thereof, each of said cross members being provided on their upper surfaces with angularly related notches extending entirely thereacross, each of the corner posts being provided with an 45 open slot with which an end notch of a

cross member registers, a plate supported by the corner posts and positioned above the cross members, the lower face or surface of said plate being substantially coplanar with the upper surfaces of the cross members, the marginal portions of the plate being provided with recesses registering with the notches or recesses of the cross members, said members being arranged outwardly of the corner posts and the plate positioned 55 inwardly thereof, an elongated arm associated with each registering notch and recess, each registering notch and recess providing an opening in which the arm is freely 60 slideable, and means carried by the opposite end portions of the arms for limiting the movement of said arms in either direction.

2. A drier of the class described comprising upwardly and inwardly inclined corner posts, sills connecting the lower ends of the posts, cross members connecting said posts, each of said cross members being provided on their upper surfaces with angularly related notches extending entirely 65 thereacross, a plate supported by the corner posts and positioned above the cross members, the lower face or surface of said plate being substantially coplanar with the upper surfaces of the cross members, the marginal portions of the plate being provided with recesses registering with the notches or recesses of the cross members, said members being arranged outwardly of the corner posts and the plate positioned 70 inwardly thereof, an elongated arm associated with each registering notch and recess, each registering notch and recess providing an opening in which the arm is freely 75 slideable, and means carried by the opposite end portions of the arms for limiting the movement of 80 said arms in either direction.

In testimony whereof I hereunto affix my signature.

JOSEPH PRIER.
